CLAIM

The ornamental design for a binnacle for automobile or replica thereof, as shown and described.

DESCRIPTION

FIG. 1 is a right isometric view of a binnacle for automobile or replica thereof;

FIG. 2 is a front elevation view of FIG. 1;

FIG. 3 is a top plan view of FIG. 1;

FIG. 4 is a right side elevation view of FIG. 1;

FIG. 5 is a rear elevation view of FIG. 1;

FIG. 6 is a left isometric view of FIG. 1; and,

FIG. 7 is a left side elevation view of FIG. 1.

1 Claim, 7 Drawing Sheets
